UNITED STATES PATENT OFFICE.

BENJAMIN F. OVERTON AND LOUIS E. BRYANT, OF OMEN, TEXAS.

DESIGN FOR A QUILTING-FRAME STAND.

SPECIFICATION forming part of Design No. 28,999, dated July 5, 1898.

Application filed June 2, 1898. Serial No. 682,406. Term of patent 14 years.

To all whom it may concern:

Be it known that we, BENJAMIN F. OVERTON and LOUIS E. BRYANT, citizens of the United States, residing at Omen, in the county 5 of Smith and State of Texas, have invented and produced a new and useful Design for a Quilting-Frame Stand, of which the following is a specification.

This invention relates to a new and original 10 design for a quilting-frame stand; and it has for its object to provide a design of this character which shall be both useful and ornamental.

The leading feature of the design resides in 15 an open upright rectangular frame provided at the top with a flat horizontal shelf-piece having a pair of narrow bracket-ledges projecting from its front edge at opposite ends thereof, and a vertical top board rising from 20 the rear edge of the shelf-piece and of an approximately rectangular form, said vertical top board being provided at its crest or top edge with a centrally-located semicircular lobe projection, with a series of substantially 25 semicircular scallops in its edges at both sides of said lobe projection, and with a rectangular mirror-panel at its front side.

The minor features of the design are the vertical top board of the stand, having at its 30 front side a plurality of offstanding headed projections and triangular pieces arranged on the top shelf-piece at the ends thereof, in the angle between said shelf-piece and the vertical top board.

35 In the drawing the figure is a perspective view of a quilting-frame stand embodying the herein-described design.

Referring to the drawing, the numeral 1 designates an open upright rectangular frame 40 provided at its lower corners with inverted-

U-shaped leg-brackets 2, disposed in vertical planes. At the top the said open upright rectangular frame 1 is provided with a flat horizontal shelf-piece 3, having a pair of narrow bracket-ledges 4 projecting from its front edge at opposite ends thereof, said narrow bracket projections having polygonal front edges 5. The upright rectangular frame 1 is further provided with a vertical top board 6, rising from the rear edge of the shelf-piece 3, 45 and of an approximately rectangular form. The said vertical top board is provided at its crest or top edge with a central semicircular lobe projection 7 and at its top corners is provided with obliquely-disposed lobes 8, which 50 latter lobes are bounded at their opposite sides and outer ends by approximately semicircular scallops 9. At its front side the vertical top board 6 is provided with a centrally-arranged rectangular mirror-panel 10 and 55 with a plurality of offstanding headed projections 11, and the design is completed by the triangular pieces 12, which are arranged on top of the shelf-piece 3 at the ends thereof and lie in the angle between the shelf-piece 60 and the front side of the top board 6.

Having described our invention, what we claim, and desire to secure by Letters Patent, is—

The design for a quilting-frame stand, here- 70 in shown and described.

In testimony that we claim the foregoing as our own we have hereto affixed our signatures in the presence of two witnesses.

BENJAMIN F. OVERTON.
LOUIS E. BRYANT.
